ATTORNEY.

UNITED STATES PATENT OFFICE

FREDERICK WESTERBECK, OF UNIVERSITY CITY, MISSOURI

CONTAINER

Application filed February 5, 1930. Serial No. 425,942.

This invention relates to sheet metal containers, one of the objects being to produce a container that may be easily and positively opened by means of a simple opening device cooperating with a flange on the container. More specifically stated, an object is to prevent displacement of the opening device during the opening operation.

A further object is to produce a simple means for retaining the opening device in its operative position, so as to prevent accidental displacement that has heretofore been due to looseness at the means for securing such opening devices, and also to accidentally bending of said devices before they are used to open the containers.

Prior to this invention, containers have been flanged to receive screw drivers, coins, etc. which are turned while in contact with the flanges, so as to open the containers. However, the old flanges of which I am aware have been so formed that they tend to deflect the opening device from the flanges during the opening operation, and it is difficult to retain the opening device in contact with the flanges while exerting the pressure required to open the container. The inclined flanges herein shown are adapted to receive various kinds of opening devices, and this new flange arrangement does not tend to deflect, or displace, the opening device during the opening operation.

Containers have also been provided with cams, and the like, pivotally connected to the container bodies and engaging the closures to serve as opening devices. One of the objections to the old devices of this kind lies in the fact that looseness at the pivotal connection would result in displacement of the opening device from the closure, when the device was operated for the purpose of opening the closure. Furthermore, the flanges, or beads, engaged by such old devices were so formed that the opening device was likely to be displaced therefrom at the beginning of the opening operation, and the old opening devices carried by the containers were also subject to the danger of being accidentally bent and thereby rendered inoperative.

Therefore, a specific object of the present invention is to eliminate all danger of displacement that has heretofore been due to slippage, bending or looseness of the opening device. I will hereafter show how this important result is accomplished by means of a simple and inexpensive device, that can be very easily applied to the container, without requiring a high degree of accuracy in either the manufacture or assembling of the device.

With the foregoing and other objects in view, the invention comprises the novel construction, combination and arrangement of parts hereinafter more specifically described and illustrated in the accompanying drawing, wherein is shown the preferred embodiment of the invention. However, it is to be understood that the invention comprehends changes, variations and modifications which come within the scope of the claim hereunto appended.

In the preferred form of the invention, the container comprises a body member and a closure member, one of said members being provided with an inclined flange, and the other member being provided with an opening device including a thrust element confined between the inner face of said inclined flange and a wall of the container, so as to prevent displacement of the opening device during the opening operation. More specifically stated, the body of the container and the closure may be provided with converging flanges, and the opening device may be in the form of a lever interlocked with said flanges. The lever may have an extended thrust element confined by one of the flanges, and an extended retaining element confined by the other flange.

Fig. 1 is a side elevation of a container embodying the features of this invention.

Fig. 2 is an enlarged fragmentary view showing how the opening device may be interlocked with flanges on the container.

Fig. 3 is a section on the line 3—3 in Fig. 2.

Fig. 4 is a view similar to Fig. 1 illustrating a modification.

To illustrate one form of the invention I have shown a container comprising a sheet metal body member 1 having a peripheral

closure seat 2 at its upper margin, and a flat, annular two ply peripheral flange 3 inclined upwardly from the bottom of said closure seat.

5 The sheet metal closure 4 has a lower margin surrounding and frictionally engaged with the outer face of said closure seat 3. The closure is also provided with a flat, annular two ply flange 5 inclined downwardly 10 from the upper portion of its lower margin.

The two ply flanges 3 and 5 are easily formed by extending and bending the sheet metal. The inner faces of the plies of each flange preferably contact with each other, 15 as this produces a strong flat flange which materially reinforces the container, and the outer edge of the flange is relatively sharp, so it will not tend to displace a screw driver, coin, or other article used in opening the container.

20 However, in the preferred form of this invention, the opening device is carried by the container, and to illustrate this feature I have shown a lever 6 pivoted at 7 to the body member 1, and provided with a thrust element 8 confined between the inner face of the flange 5 and the container wall formed by the lower margin of the closure. The lever 6 has a finger-receiving member 9 which 25 may be depressed to elevate the thrust member 8, and since this thrust member is confined by the inclined flange 5, it cannot be displaced during the opening operation. This practically eliminates the liability of 30 displacement, and insures the desired opening of the container when the required force is applied to the opening device.

35 As a further safeguard, to prevent accidental bending, or displacement, of the thrust element of the opening device, the lever 6 may be provided with a downturned retaining element 10 confined between the inner face of the inclined flange 3 and the adjacent wall of the container. This downturned retaining 40 element cooperates with the upturned thrust element 8 to prevent bending or other displacement of the thrust element, and both of said elements can be easily formed by splitting and bending the upper extremity of 45 the lever 6.

50 The lower portion of this lever is preferably closely fitted to the container, but this is not essential, and it is not necessary to firmly secure the lever at the pivot 7, as looseness of the lever will not result in displacement during the opening operation. The lever herein shown is offset at 11 (Figure 3) and it extends upwardly from this offset to an inturned portion 12 which extends between the adjacent outer edges of the separated flanges 3 and 5 and merges into the terminal elements 8 and 10. These terminal elements lie in the inwardly flaring space between the converging flanges, and they are 55 thus interlocked with the container to posi-

tively prevent displacement of the thrust member 8 of the opening device.

Since the opening device can be securely interlocked with the container, it is not absolutely necessary to provide any other means 70 to secure said device, and as a simple illustration of this feature I have shown, in Fig. 4 a lever 6' which is not pivoted to the container. This lever may in all other respects conform to the lever shown in Figures 1, 2 75 and 3, but of course other forms of opening devices conforming to the following claim may be interlocked with the container, or the specific flange arrangement may be advantageously used with any other suitable opening device. 80

I claim:

A sheet metal container comprising a body member and a closure member, each of said members being provided with a peripheral inclined flange, the outer edges of said inclined flanges being adjacent to each other, the inner face of each flange being at an acute angle to the adjacent wall of the container to provide an inwardly flaring space between them and a lever extending between said adjacent outer edges of the flanges, said lever having an upturned thrust element engaging the inclined inner face of the flange on said closure member and a downturned retaining element engaging the inclined inner face of the flange on said body member so that said lever is interlocked with and confined by said inclined flanges. 90

In testimony that I claim the foregoing I 100 hereunto affix my signature.

FREDERICK WESTERBECK.
